T. MOORE.

Stove Pipe Thimble.

No. 12,639.

Patented April 3, 1855.

UNITED STATES PATENT OFFICE.

THOMAS MOORE, OF FAIR HAVEN, VERMONT.

STOVEPIPE-TUBE.

Specification of Letters Patent No. 12,639, dated April 3, 1855.

To all whom it may concern:

Be it known that I, THOMAS MOORE, of Fair Haven, in the county of Rutland and State of Vermont, have invented a new and 5 useful Improvement of Stovepipe-Tubes, called a "double adjusting stovepipe-tube," of which the following is a full and exact description.

It consists of two sets of cylindrical tubes 10 each, (marked *d d*) the inner one of sheet iron and the outer one of sheet zinc. One end of each set of said tubes are fastened to metallic heads (marked *c*) which heads have an outer convex surface so that when 15 applied to a partition the edges of the heads will only come in contact with the same. Said tubes are so adjusted that they can be connected by inserting the end of one into that of the other and when thus connected 20 will admit of a free circulation of air in the

spaces between them (marked *E*) by means of opposite appertures in either head. In connecting said sets of tubes as above described the length can be graduated as desired from the length of one set of tubes to 25 nearly that of both.

What I claim and desire to secure by Letters Patent is,

The double and adjustable concentric tubes, or stove pipe thimbles constructed in 30 the manner described for the purposes set forth.

In witness whereof I have hereunto subscribed my name the 19th day of January 1855.

THOMAS MOORE.

Witnesses:

J. CAPEN,
H. L. LEONARD.
